UNITED STATES PATENT OFFICE.

CHARLES ALMON JACKSON, OF LAWRENCE, ASSIGNOR TO THE JACKSON ELECTRIC ENGINE COMPANY, OF BOSTON, MASSACHUSETTS.

ELECTRIC ENGINE.

SPECIFICATION forming part of Letters Patent No. 320,137, dated June 16, 1885.

Application filed January 15, 1885. (No model.)

To all whom it may concern:

Be it known that I, CHARLES ALMON JACKSON, a citizen of the United States, residing at Lawrence, in the county of Essex and State of Massachusetts, have invented certain new and useful Improvements in Electric Engines; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 This invention relates to electric motors, and belongs particularly to that class in which a reciprocating armature is used in connection with a series of commutators and brushes in lieu of employing the revolving armature, as 20 in the ordinary dynamo-machines for generating power.

25 My invention consists, essentially, in the peculiar adaptation of a crank to a driving-shaft, whereby an increased length of crank is obtained with but a minimum traverse or throw of the armature.

30 Heretofore there has been a serious defect in electric motors of this class, consisting in the great distance between the magnets, and the loss of attraction, motion, and power while the armature is passing over it. Owing to this defect motors of this class have not gone into general use. It becomes, therefore, very desirable to reduce to a minimum the travel 35 of the armature and the interval between the magnets. Now, I obtain this minimum of travel in my invention, which is thus briefly described, by saying that the crank is attached to the shaft, but not to the cross-head within 40 which it travels and from which it receives intermittent thrusts; but the cross-head is attached directly to the connecting-rod carrying the armature, and its extreme travel or thrust is but slightly more than the length of 45 the radius of the bore of said cross-head, while the crank, after the thrust given, is free to travel the length of a radius without carrying the armature with it, thus obviating unnecessary throw of said armature, and 50 when the crank has traveled one hundred and

eighty degrees the cross-head again exerts an active thrust in the opposite direction for the length of a radius. Now, in case the latter and its connecting-rod were directly attached to a crank of the same radius, it would be 55 forced to travel with it, and in lieu of moving only the length of a radius would be obliged to travel through one hundred and eighty degrees, or twice the radius, to reach the same point attained in my method. Thus 60 I save the travel in a great measure, and still obtain the crank leverage. I have, therefore, endeavored to obviate any excessive travel of the armature by the relation of the operative parts to be hereinafter described. 65

My invention further consists in the general arrangement of the electro-magnets and their disposition with respect to the driving-shaft; also, in the construction and disposal of the commutators and brushes, whereby proper thrusts 70 are obtained from the armatures and magnets to rotate the main shaft, and ready means are secured for reversing the motor at the will of the operator, or stopping it entirely. This arrangement of the crank permits the thrust or 75 power to be exerted at the time when it is most effective—that is, when said thrust is at right angles to a radius instead of in line with it.

The drawings represent, in Figure 1, a general plan or diagrammatic view of the current system as applied to the electro-magnets and armatures forming part of an electric motor embodying my improvements. Fig. 2 represents a horizontal section of the motor, while 85 Fig. 3 is a vertical transverse section through one of the cross-heads at the commencement of an active thrust. Fig. 4 shows the position of the cross-head relatively to the crank during the inactive portion of revolution of the 90 latter. Fig. 5 is a modified form of the crank-disk. Figs. 6, 7, 8, and 9 are diagrams to show the position of the various co-operating parts at the commencement of one-quarter of a complete revolution of the main shaft. Fig. 95 10 is an isometric view of one of the commutators, and Fig. 11 is a section on line α α of Fig. 10. Fig. 12 is a vertical cross-section of the standards in which the cross-heads reciprocate. 100

In these drawings, A A represent two parallel standards or housings, forming a general support for the motor. These standards are constructed with vertical polygonal openings 5 $a^5 a^6$, &c., V-shaped at top and bottom to form ways in which to support and permit the travel of a series of cross-heads $B^5 B^6$, &c., centrally bored at $b^5 b^6$, &c., and provided with arms $c^5 c^6$, &c., in cross-section similar to the 10 openings $a^5 a^6$, in which they reciprocate. To the extremities of these arms are attached the connecting-rods $C^5 C^6 C^7 C^8$, the latter being secured to swinging lever-arms $d^5 d^6$, &c., and suitably disposed in bearings, while to the 15 lower extremities of said levers are attached the armatures $D^5 D^6$. Thus when the current is passed through the electro-magnets the armatures are influenced and a thrust is imparted to the main shaft E by means of the 20 operative parts above described.

It will be observed that the openings $b^5 b^6$ of the cross-heads are constructed of considerable diameter and made for the purpose of containing circular disks $e^5 e^6$, which latter 25 revolve within them, and are pivoted and secured to the shaft by means of cranks $f^5 f^6$, &c., and crank-pins $g^5 g^6$, &c. Thus the main shaft is composed of a series of short shafts supported upon and suitably journaled in a 30 number of posts, F F, &c.

The electro-magnets are arranged in pairs, as shown at A' B' C' D' E' F' G' H', and similar corresponding pairs at a' b' c' d' e' f' g' h'. In this nomenclature I have adopted a certain 35 system of lettering to correspond with a continuous current which is shifted at four different successive intervals of time to act upon a different set of instrumentalities each time, which latter are operated by the magnets then 40 rendered effective by the shifting of the current. Thus the exponents of the letters used in designating said magnets always have the same exponent whenever they are employed simultaneously—that is, when the current is 45 employed to operate the electro-magnets A' A' it also traverses the electro-magnets C' C' a' a' c' c' at the same time and renders them active likewise. By this system the parts co-operating with each other simultaneously at 50 any given portion of the stroke or revolution of the shaft are easily ascertained in the description of the operation of said machine.

Suitably disposed and fixed upon one end of the shaft E are the commutators I' J' K' L', 55 adapted by means of their brushes i' j' k' l' to make and break the circuit at proper intervals of time with respect to the main shaft, by which their co-operating parts shall actively affect said shaft to maintain it in rotary 60 movement. The commutators are four in number, and in the present case are compound for the purpose of enabling the driving-shaft to be reversible in its rotations or be stopped entirely. For this purpose I have made the 65 commutators compound—that is, each individual one consists of three disks, two out-

side or exterior ones (marked $o^5 o^6$) and the dividing-disk p, composed entirely of insulating material. The insulating material is indicated in this instance and in all others by black spaces, the metal by white. The disks 70 $o^5 o^6$ are similarly shaped, but have three-quarters of their peripheries of insulating material, m m, while the other quarters, n n, of metal, are adapted to effect metallic contact with each brush at proper times. Furthermore, the disks o^5 upon one side of the four commutators are so disposed that the metal contact-surfaces stand quartering, and each one shall occupy a distinct quadrant. On the other 80 hand, each of the corresponding disks, o^6 , on every commutator are similarly arranged in quadrature; but the two disks, $o^5 o^6$, on the individual commutators are so set with respect to each other that the metallic surfaces n n 85 shall be diametrically opposite. Thus in reversing the motor it is only necessary to shift the brushes, which are mounted in a properly-pivoted carriage or sliding support, M, from one commutator o^5 to a second but diametrically-arranged co-operating commutator, o^6 . Thus a pull or thrust is exerted in an opposite direction upon the shaft, and the latter is started in a reverse path of rotation from that just before accomplished. 95

To stop the machine it is only necessary to move the brushes by means of the lever and carriage M to a position midway between the two disks, $o^5 o^6$, forming each commutator; or, in other words, allow them to rest upon 100 the insulating-disks p. Thus all the helices or electro-magnets are for the time being rendered inactive, and the machine remains stationary.

The actuating instrumentalities by which 105 alternate thrusts exerted upon the cross-head effect and transmit their force to the shaft in order to rotate the same is accomplished by means of circular disks $e^5 e^6$, which correspond to the crank in an engine. These disks are 110 centrally and loosely pivoted upon crank-pins $g^5 g^6$ eccentrically disposed upon cranks $f^5 f^6$, the latter, however, being centered upon those portions of the shaft which go to constitute the main shaft E, all as heretofore 115 premised. Thus each of the crank-disks $e^5 e^6$, &c., rotates intermittently upon the interior periphery of the cross-head inclosing it. As the cross-heads reciprocate transversely of the shaft by the influence of the current passing 120 through the helices of the electro-magnets, which latter attract the armatures attached to the lever-arms and connecting-rods secured to said cross-heads, pressure is brought to bear against said disks, which move away from the 125 thrust so exerted, and by this means the revolution of the shaft is accomplished by the movement of an "epicycle," so called.

The operation of the motor is accomplished by shunting or shifting the current successively through the circuit-wires designated by the numerals 1 2 3 4 by means of the instru-

mentality of the commutator-disks and their brushes, which latter, by passing from the insulating material to the metallic surfaces composing said disks, affect certain ones of the 5 helices to render them active, while others in the series of helices are made inactive at proper intervals of time, and so maintain a continuous succession of thrusts to rotate the shaft from which the motive power is to be furnished.

10 The battery may consist of any number of series of cells adapted to give a current of electricity most suitable for a machine of the above description, and is shown at N. The current generated therefrom has the same general direction with reference to the helices, only it is forced by means of the commutators to shift its course to render certain of the helices active, while the remainder are rendered 15 inactive.

20 The helices are arranged as shown in pairs in lieu of being single, in order to obtain more power, while the length of the armatures is accordingly extended to suit existing circumstances. It is evident from the arrangement 25 and system of the helices herein described that a second connecting-rod may be united to the rods, as shown, and in axial alignment therewith, while a secondary series of helices 30 may be disposed in rear of the first series, making the entire series two deep, and thus augmenting the power twofold upon each connecting-rod. By this means the power of the machine can very easily be greatly multiplied 35 without increasing the size very much, and at a very small expense or cost.

It must be understood from my invention 40 that the cross-heads B⁵ B⁶ B⁷ B⁸ co-operate alternately in pairs—that is, B⁵ B⁷ act together, and B⁶ B⁸—and the current is so disposed that the opposite pairs of the helices are rendered active, and thus two opposite thrusts are exerted simultaneously upon the shaft to aid its revolution. Upon reference to Fig. 1 this 45 idea is more easily explained, and so it will readily be seen that the alternate cross-heads with their operating mechanism act together simultaneously, but in different directions, as shown by arrows 1 and 2. Thus the cross-heads B⁵ B⁷ are now active, having just completed their stroke, and the helices or electro-magnets which have been employed to effect these thrusts by attraction upon the armatures D⁵ D⁷ are A' A' a' a' upon the cross-head B⁵, while the opposite helices, C' C' c' c', 50 of the similar acting pairs of electro-magnets operate the cross-head B⁷ by the armatures D⁷ D⁵. The resultant or active thrust derived from the above position of parts effects 55 positive movement of the shaft for ninety degrees or one-quarter of an entire or complete revolution. This is accomplished by means of the metallic contact-surface of its commutator I' with the brush i' during that distance which 60 directs the current No. 1 through the helices A' A' a' a' C' C' c' c', as above premised. The

instant brush i' has broken its metallic contact with its commutator the metallic contact-surface J² has completed the circuit by aid of its brush j² through the wire which conducts 70 current No. 2. The latter induces activity in the pairs of helices E² E³ e² e³ H² H³ h² h³, and their respective cross-heads B⁶ B⁸ are oppositely thrust, as shown by the arrows 3 and 4. This completes the second quarter or ninety 75 degrees of a complete revolution of the shaft, when the brush i' and its commutator have broken their metallic contact, and the armatures are free to withdraw from their helices. This position of parts is shown in Figs. 1, 6, 80 7, 8, and 9. In the four latter figures diagrammatically represented it will easily be seen that commutator I' has just broken contact with its brush i', while J² has just completed contact with its brush j²; hence the current is 85 on wire No. 2. The helices then active are E² E³ H² H³ e² e³ h² h³, while the commutators I' K³ L⁴ are inactive, with the current shunted off.

In Fig. 2 is shown a different position of parts, and the crank-disk e⁵ is then upon its 90 extreme throw to the left just commencing its active thrust, as shown more fully in Fig. 3. At this time commutator K³ is then in contact with its brush k³, and has vitalized the helices B³ B⁴ b³ b⁴ D³ D⁴ d³ d⁴, which attract their armatures, D⁵ D⁶ D⁷ D⁸, to thrust the crank-disk e⁵ simultaneously with e¹, but in the opposite direction. Upon the breaking of this current 95 commutator K³ and brush k³ have closed the circuit upon the wire conveying current No. 100 3, and the cross-heads B⁵ and B⁷ are again brought into active operation by aid of the oppositely-disposed pairs of helices from that employed upon the first quarter of the revolution. In this instance helices B³ B⁴ b³ b⁴ D³ D⁴ 105 d³ d⁴ are now active, and opposite thrusts are effected respectively to those shown by arrows 1 and 3 in the first quarter of the stroke. Metallic contact is maintained between commutator K³ and its brush k³ for ninety degrees of 110 are and thus an active thrust is obtained in order to complete the third quarter of the revolution of said shaft E.

When the current No. 3 over its wire is 115 broken by the insulating material of K³ meeting its brush, commutator L⁴ has effected metallic contact with its brush l⁴, and current No. 4 is induced through the proper wires to actively operate the helices F¹ F² f¹ f² G¹ G² 120 g¹ g², and with the armature and operating mechanism connecting the cross-heads B⁶ and B⁸, each of which are oppositely thrust from the direction taken by them on the second quarter of the revolution, as shown in Fig. 1 by arrows 3 and 4. This completes the fourth 125 quarter, and the complete revolution of the main shaft has been actively and continuously effected by the thrusts from the cross-heads resulting from the successive activity of the various pairs of helices forming the entire series. At this time, or upon the completion of 130 one entire revolution, commutator I' and brush

i' are again in contact, and current No. 1 is actively employed to operate the helices A' A' a' a' C' C' c' c' and their operating mechanism, as hereinbefore fully described.

5 To a more complete understanding of the active operation and position of parts during portions of one complete revolution, I have shown in Figs. 6, 7, 8, and 9 diagrams of the positions of the crank-disks simultaneously 10 with respect to their individual cross-heads, while below is represented the position of the commutators and their respective brushes. These four figures illustrate one-quarter of an entire revolution of the shaft E. 15 In order to insure freedom of motion to the crank-disks *c³ c⁵* when they cease their active movement, or during the time they are passing from one active position to another, it is necessary that the periphery of the cross-head 20 should be removed slightly therefrom. Now, it is evident that the crank-disks travel in arcs of circles with the shaft E as the center, and upon reference to Fig. 6 one of said cranks is 25 therein shown as just commencing the inactive portion of the revolution, with the armatures commencing to reverse their motion, and preparatory to advancing toward B³ b³, but this motion would throw the cross-head B³ against the crank and prevent its advance forward 30 motion; or, in other words, tend to drive it back to its position at the commencement of its active stroke. It is in order to prevent this antagonistic action of the cross-heads and their cranks that I have made the interior 35 periphery of said cross-heads circular, but have given them a stroke sufficient to throw them from the center to permit of the advance of the crank-disks and yet allow the armature to advance in the opposite direction required 40 without retarding said crank-disks. Thus when the disk has ceased its activity, the cross-head still advances eccentrically of its enclosing crank, and thus, while the armature is reversing its motion, the crank has reached 45 a second active position, and simultaneously therewith the cross-head, by the action of its armatures, has returned from its eccentric position, and is in readiness to again exert a positive active thrust upon the crank-disks to 50 induce positive forward motion of the main shaft. This is more fully illustrated by reference to Fig. 4 of the drawings. At the point marked *u* the active thrust from the cross-head, moving in the direction of the arrow, as 55 designated, ceases, and the latter advances the distance shown between the full and dotted lines in said drawings. During this movement the crank has advanced to the point marked *v*; but while said crank is passing from *v* to *w* the 60 cross-head, by reason of the action of the armatures thereon, as above stated, has returned to its active position concentric with its crank in readiness for an active thrust through an arc of ninety degrees.

65 In Fig. 5 is shown a slight modification, in which a small disk, *q*, is employed, suitably

mounted upon a crank, *r*. By this means I am enabled to increase the length, and consequently the power, of the latter upon the shaft to produce rotary movement.

70 By a close examination into the system and arrangement of the parts composing my invention, it is easily understood that various modifications may be introduced therein without affecting the spirit and essence of the invention; and, although I have described and illustrated the machine as being operated by four distinct active thrusts in order to complete one revolution of the driving-shaft, still 75 it is very evident that this may be easily modified by changing the number of commutators and likewise altering the length of arc comprised in the metallic surface. Thus each of the latter elements may contain only forty-five degrees of arc; hence this would necessitate 80 eight commutators and eight corresponding cross-heads. By this means the shaft would receive eight active thrusts in lieu of four, and the resultant or power obtained would be very 85 materially increased.

90

I claim—

1. In an electro-magnetic machine, the combination, with a single brush or contact device, of the compound commutators insulated with respect to each other, and with the metallic portions of their peripheries diametrically opposed, whereby the direction of the motor may be reversed by the shifting of the brush, substantially as herein set forth.

95

2. In an electro-magnetic engine, the combination of a series of helices and their co-operating mechanism, with a driving-shaft provided with a pair of cranks and a pair of cross-heads actuated by said helices and provided with openings *b³*, which inclose said cranks, 100 the arrangement of cranks and cross-heads allowing the latter to exert opposite alternate thrusts upon said shaft for effecting the rotation thereof, substantially as set forth.

105

3. In an electric motor, the combination, 110 with a main shaft having a crank, of a cross-head provided with a recess to inclose said crank, and devices for reciprocating said cross-head to rotate said shaft by its action on said inclosed crank, the opening or recess in said 115 cross-head being of sufficient size and said cross-head being given sufficient thrust to prevent contact between said cross-head and said crank while the latter is passing from an inactive position to an active position, substantially as set forth.

120

4. In an electric motor, the combination of a cross-head having a circular opening, *b⁵*, with a main shaft provided with a crank having a disk arranged within said opening, the 125 impulses of said cross-head being communicated to said disk by contact of the wall or side of the opening therewith, and thereby causing the rotation of said main shaft, substantially as set forth.

130

5. In an electric motor, the combination, 135 with a shaft, a pair of cranks on said shaft,

and a pair of cross-heads, each provided with an opening, b^5 , which respectively inclose said cranks, of two commutators, their brushes, and the electric generating and conducting devices 5 which cause said cross-heads to act alternately on said cranks and shaft, substantially as set forth.

6. The combination, with a shaft, adapted to furnish motive power, its cranks inclosed 10 by and rotating within reciprocating cross-heads, and the co-operating armatures and helices, of a series of commutators and brushes and the necessary electric connections, whereby 15 said commutators are connected to said helices, and effect successive active thrusts upon said shaft to compel rotation thereof, substantially as herein described.

7. In an electro-magnetic machine, the combination, with a single brush, of a compound 20 commutator provided with two diametrically-opposed metallic contact-surfaces and a disk composed entirely of insulating substance, whereby upon shifting of the brush thereon the machine is stopped, substantially as stated.

8. In an electro-magnetic machine, the combination, with the main shaft, reciprocating armature, and cross-head, of a crank disposed thereon, said crank being provided with a disk which is disconnected from and actuated intermittently by the said cross-head, to which 30 is secured the said reciprocating armature, substantially for purposes herein set forth.

9. In an electro-magnetic engine, the combination of a main shaft and a crank formed thereon with a reciprocating armature, an electro-magnet, and a cross-head which is actuated by said magnet and armature, said cross-head being unconnected to said main shaft, but intermittently engaging therewith to rotate 35 said shaft, substantially as set forth.

In testimony whereof I affix my signature in presence of two witnesses.

CHARLES ALMON JACKSON.
